Primary Examiner — Ruth McInroy(74) *Attorney, Agent, or Firm* — Morrison & Foerster LLP(57) **CLAIM**

We claim the ornamental design for a part of a vacuum cleaner, as shown and described.

DESCRIPTION

FIG. 1 is a front perspective view from one side of a part of a vacuum cleaner showing our new design;

FIG. 2 is a front perspective view from the opposite side shown in FIG. 1;

FIG. 3 is a side view thereof;

FIG. 4 is a side view of the opposite side of FIG. 3; and, FIG. 5 is a front view thereof.

The details shown in broken lines form no part of the claimed design.

1 Claim, 5 Drawing Sheets(56)
